UNITED STATES PATENT OFFICE

CONRAD LUTTEROPP, OF STOCKHOLM, SWEDEN, ASSIGNOR OF ONE-HALF TO ANDERS LINDAHL, OF STOCKHOLM, SWEDEN

CALCULATING MACHINE

Application filed November 12, 1924, Serial No. 749,459, and in Sweden November 27, 1923.

This invention relates to calculating machines and especially to that type of calculating machines described in my prior application Serial No. 657,148 filed August 13, 1923, now Patent No. 1,662,526, which uses a totalizing mechanism mounted in a movable carriage.

In such types of calculating machines the transmission of power from the stationary 10 actuating mechanism to the numeral wheels of the totalizer to rotate said wheels must not interfere with the displacement of the carriage, nor with the transfer operation. To this end it has been proposed to effect 15 such transmission of power by means of impulse wheels, as in the form of pinions moved step by step and in each movement brought into the path of projections on the numeral wheels to give the latter an impulse 20 to rotate them one step in the desired direction. In such operation, however, it may happen, if the handle of the machine is moved too powerfully or rapidly that the impulse imparted to any numeral wheel will 25 be so effective as to move the wheel more than one step at a time.

This invention has for its purpose to overcome said difficulty by the provision of a 30 positively controlled power transmission to the totalizer wheels.

The invention is characterized, chiefly, by the provision, in the actuating mechanism of the said wheels, of gears adapted to be brought into and out of operative relation 35 to said wheels in such a way that said relation is brought about immediately in advance of the commencement of the operation of said actuating mechanism and is released after the completion of said operation.

40 In this way there will exist during the performance of a calculating operation a positively controlled connection between the actuating mechanism and the numeral wheels of the totalizer and furthermore all masses 45 set into motion during the performance of the calculating operation will be fully brought to their positions of rest before said connections are released.

The invention will be more fully understood by reference to the accompanying

drawing in which the invention is illustrated by way of example. It is to be noted that only those parts necessary for an understanding of the invention are shown and that, since the means individual to the several 55 numeral wheels are all alike, only those means belonging to one such numeral wheel are shown.

In the drawings, Figure 1 is a side elevation of a numeral wheel of the totalizer and 60 parts of the corresponding actuating mechanism.

Fig. 2 is a cross section of the crank shaft 65 of the machine with two intermediate driving shafts controlled thereby.

Fig. 3 shows the outlines of a calculating machine with the members according to the invention indicated in their actual position with respect to each other.

The invention is illustrated as applied to 70 a calculating machine of the type and design set forth in my Patent No. 1,662,526 to which patent is referred for obtaining a more detailed description of the machine and its operation.

With reference to Fig. 2, 1 is the crank shaft of the machine which is connected by the toothed sector 2 to a pinion 3 rotatably mounted on the shaft 4 and provided with a one-way clutch in the form of a pawl 5 80 adapted to cause the shaft 4 to move with the pinion 3 when the shaft 1 is rotated in one direction. The pinion 3 is in mesh with a pinion 6 pivoted to a shaft 8 and provided with pawl 7 similar to the pawl 5 to cause 85 the shaft 8 to rotate upon the rotation of the shaft 1 in the other direction. The shaft 4 constitutes the driving shaft for the actuating mechanism of the numeral wheels of the totalizer on the carriage, and the shaft 8 90 is the transfer operating shaft.

The shaft 4 is connected by means clearly shown and described in the patent above referred to which includes among other members a selector 30 a counting drum 40, counting spindles 50, and bevel gears 121, to intermediate shafts 9 each individual to a corresponding one of the numeral wheels of the totalizer on the carriage. In the drawings one such intermediate shaft is shown at 9 100

and the corresponding totalizer wheel is shown at 10.

The shaft 9 carries a bevel gear wheel 11 meshing with a bevel gear 12 carried by the shaft 13 mounted stationary in the machine frame. Secured to the bevel gear 12 is a spur gear 14 meshing with a pinion 15 on the shaft 16. The shaft 16 is mounted in a carrier 17 rotatably mounted on the shaft 13. Pivoted to the carrier 17 is one end of a link 18 the other end of which is provided with an extended slot 19 in which plays the shaft 4. The shaft 4 carries a cam disk 20 upon the edge of which facing the carrier 17 rides a roller 21 carried by the link 18. Secured to the lowermost end of the link 18 is a spring 22 tending to move the link with the roller 21 towards the cam disk 20.

The operation of the mechanism above described is as follows: By turning the carrier 17 on the shaft 13 the pinion 15 may be brought into and out of engagement with a pinion secured to the respective numeral wheel 10 which is adjusted to position for exact engagement by means of the pawl 23.

In Fig. 1, the mechanism is shown in its normal or disengaged position. In this position the roller 21 bears against a concave portion of the periphery of the cam disk 20.

To actuate the numeral wheels of the totalizer the shaft 1 is rotated in the direction indicated by the arrow *a*, Fig. 2 through an angle corresponding to the toothed sector 2 the shaft 4 being thereby caused to rotate in the direction of the arrow *b*. At the commencement of this rotation the cam disk 20 lifts the roller 21 with the link 18 against the action of the spring 22 so that the carrier 17 is caused to rotate around the shaft 13 to such an extent as to bring the pinion 15 into engagement with the pinion of the respective numeral wheel 10. When this engagement is fully brought about there will exist a positive connection between the actuating shaft 9 and the numeral wheel under consideration. The power transmission means between shaft 4 and shaft 9 are constructed and arranged as described in the patent above referred to so as to bring about an operative connection between said shafts only after the shaft 4 has been rotated to such an extent as to bring the pinion 15 into engagement with the pinion of its corresponding numeral wheel 10. During the continued rotation of the shaft 1 said engagement is maintained and the numeral wheel is thus caused to rotate by a positive power transmission preventing any unintentional movement of the numeral wheel, however violent the movement may be. The rotation of the numeral wheel 10 takes place during a comparatively small portion of the rotation of the shaft 4, whereupon the connection between the shaft 4 and the shaft 9 ceases. When the shaft 4 approaches the end of its rotation the roller 21

again engages the concave portion of the cam disk 20 thereby permitting the spring 22 to contract and move the link 18 with it so as to cause the latter to restore the carrier 17 and thereby bring the pinion 15 out of engagement with the pinion of the corresponding numeral wheel 10. When this engagement ceases the numeral wheel with its actuating means will, as stated, be fully at rest so that there exists no tendency for the numeral wheel to leave the position into which it has been adjusted.

It is to be noted that in the drawings the invention has been shown as applied to one numeral wheel only. In fact the arrangement is, of course, identical for each of the remaining numeral wheels of the totalizer. In such case, the carrier 17 may, preferably, be common to the driving wheels 15 of all of the numeral wheels.

It is further to be noted that the invention may be applied to numeral wheels other than those of the totalizer.

For instance, it may be applied to recording or type wheels of any kind in connection with which the effect resulting from this invention is necessary or desirable.

Having now described my invention I declare that what I claim is:

1. In a calculating machine of the type set forth including a totalizing mechanism comprising a set of numeral wheels, a shaft common to said wheels and a movable carriage in which the shaft is mounted; the combination with a crank shaft, of a spur gear for each numeral wheel, a stationary shaft on which the spur gears are loosely mounted, a swingable frame mounted on said shaft, a shaft carried by said frame, pinions on said last mentioned shaft in constant mesh with said spur gears, a counting drum from which to rotate said first mentioned spur gears upon rotation of said crank, other means operated from the crank shaft when the latter is oscillated in one direction to upwardly swing said frame and the spur gears carried by the frame to cause each spur gear therein to mesh with a separate one of the numeral wheels and remain in mesh therewith during the major portion of the movement of the crank shaft and then be moved out of mesh, said means including a cam and a link longitudinally operated thereby and connected to said swingable frame.

2. The combination with a laterally shiftable carriage and number wheels and their driving wheels mounted thereon; of shafts rotated in accordance with the digits set up on the machine, spur gears separately rotated from said shafts, a shaft on which said gears are loosely mounted, a pivotal frame mounted on the latter shaft, pinions in said frame each maintained in mesh with a spur gear under all conditions, a general operator, a cam shaft and a cam thereon, means to cause unidirectional operation of said cam shaft at each

- operation of said general operator, and a link connected to the frame and operated by said cam to swing the frame so as to bring each pinion into mesh with a separate one of the driving wheels and remain in mesh therewith
- 5 during the major portion of the movement of the crank shaft and then be moved out of mesh before the operation of said general operator is completed.
- 10 3. In a calculating machine the combination with a calculating drum, number discs and their associated driving wheels, a spur gear shaft, spur gears loose thereon and simultaneously operated by separate rotatable pinions and shafts from said drum in accordance with the number set up; of a crank shaft, a sector thereon, a counter shaft, a gear wheel thereon arranged for unidirectional rotation and meshing with said sector, a cam on the
- 15 counter shaft, a frame pivoted on the spur gear shaft, pinions in the frame in permanent mesh with said spur gears, a link pivoted at one end to the frame and having its other end supported by the counter shaft, a spring to retract the link and frame and a cam roller on the link engaged by the cam.
